UNITED STATES PATENT OFFICE.

FREDERICK C. BLANCHARD, OF DETROIT, MICHIGAN, ASSIGNOR TO DETROIT LUBRICATOR COMPANY, OF DETROIT, MICHIGAN, A CORPORATION OF MICHIGAN.

LUBRICATOR.

Application filed August 31, 1922. Serial No. 585,397.

The invention relates to lubricators and refers more particularly to locomotive lubricators. The invention has for its object the provision of a unit construction of locomotive lubricator having a plurality of lubricant compartments which respectively communicate with cylinders using steam at different pressures. With this and other objects in view, the invention resides in the novel features of construction and combinations and arrangements of parts as more fully hereinafter set forth.

In the drawings:

Figure 1 is an elevation of a lubricator embodying my invention;

Figures 2, 3 and 4 are cross sections respectively on the lines 2-2, 3-3 and 4-4 of Figure 1;

Figure 5 is a cross section on the line 5-5 of Figure 2.

In compound locomotives, the high pressure cylinders use a different lubricating oil from that used in the low pressure cylinders, and heretofore separate lubricators for the high and low pressure cylinders have been employed. With my construction, different lubricating oils are fed to the high and low pressure cylinders from a single lubricator.

As shown in the drawings, 1 is the condensing chamber of the lubricator in the upper portion of the body, and 2 and 3 are separate lubricant chambers which contain the different lubricating oils, in the lower portion of the body, these lubricant chambers being separated by the transverse partition 4 formed integral with the body.

5 and 6 are feed valves adjustably mounted at the lower ends of the lubricant chambers 2 and 3 respectively for controlling the passage of the lubricating oils from these lubricant chambers through the outlet pipes 7 to the high pressure and low pressure cylinders respectively. Each feed valve is adapted to variably restrict the axial passageway 8 in the nozzle 9, this passageway communicating with an outlet pipe 7 through the vertical passageway 10 and the lateral passageway 11.

The lubricating oil is forced from each lubricant chamber by the hydrostatic head of water in the condensing chamber. Both the condensing chamber and the lubricant chambers are subjected to full boiler pressure and by means of the equalizing passages 55 the points where the lubricating oil leaves

the lubricator are also subject to full boiler pressure so that the hydrostatic head of water in the condensing chamber above the lubricant chambers is the force which drives the lubricating oil out of the reservoirs past the feed valves and through the nozzles and upwards to the delivery points. The lubricating oil is then picked up by the stream of steam, and water which is passing through each outlet pipe due to the fact that the pressure at the steam chest where the oil is introduced for lubrication is always less than the full boiler pressure. The fact that the oil is of lower specific gravity than the water also helps to float it up through the feed valve 70 nozzle and vertical passageway, but the principal force is due to the hydrostatic head of water in the condensing chamber. The steam from the boiler is admitted through the pipe 12 at the top of the lubricator body and above 75 the condensing chamber 1 and controlled by the valve 13. Some of this steam condenses in the condensing chamber 1 and some is led to the lateral passageways 11 connecting 80 into the outlet pipes 7 by means of the outer and inner equalizing passageways 14 and 15 respectively leading from the upper end of the lubricator body above the condensing chamber, there being a separate equalizing 85 passageway for each lubricating oil outlet pipe. The inner equalizing passageways are formed in the wall of the condensing chamber, while the outer equalizing passageways are formed by bent pipes.

Some of the water formed by the steam 90 condensed in the condensing chamber 1 is adapted to flow into the lubricant chamber 2 through the upper vertical passageway 16 opening into the lower end of the condensing chamber, the lateral passageway 17 opening 95 into the lower end of the upper vertical passageway 16 and the lower vertical passageway 18 opening into the lower portion of the lubricant chamber at 19 and adapted to communicate with the lateral passageway 17. This lateral passageway is controlled by the valve 20 adjustably mounted in the front side of the lubricator body. Some of the water formed by the steam condensed in the condensing chamber 1 is adapted 100 to flow into the lubricant chamber 3 through the upper vertical passageway 16, the lateral passageway 17, the second lateral passageway 21 adapted to communicate with the lateral passageway 17 and passing 105 110

through the transverse wall 4 and the lower vertical passageway 22 which opens into the lubricant chamber near its lower end through the port 23.

5 The lubricant chamber 2 communicates with the axial passageways 8 in the nozzles 9 through the vertical passageway 24 formed in a boss upon the transverse wall 4 and the lateral passageway 25 extending longitudinally at the bottom of the lubricator body and opening into the annular recesses 26 below the nozzles 9, these recesses in turn being adapted to communicate with the passageways 8 through the spaces 27 between 10 the valves 5 and their respective nozzles 9. The lubricant chamber 3 also communicates with its respective passageways 8 in the nozzles 9 through the vertical passageway 28 formed in a boss upon the transverse wall 4, the lateral passageway 29 extending longitudinally at the bottom of the lubricator body and opening into the annular spaces below the nozzles, which latter in turn are adapted to communicate with the nozzle 15 passageways.

20 The lubricant chambers 2 and 3 may be filled with the lubricating oils through the filler plugs 30 and 31 respectively.

25 In operation, steam entering the pipe 12 from the boiler passes into the condensing chamber 1 and also the outer and inner equalizing passageways 14 and 15 respectively for each lubricant compartment. The steam entering the condensing chamber condenses and the water formed thereby passes 30 downwardly through the upper vertical passageway 16, the lateral passageway 17 and then to the lower vertical passageway 18 into the lower portion of the lubricant compartment 2 as well as the lateral passageway 21 and lower vertical passageway 22 into the lower portion of the lubricant compartment 3. This water displaces the lubricating oils in these compartments which pass downwardly through the vertical passageways upon the transverse wall 4 and to the axial passageways in nozzles through the lateral passageways extending longitudinally at the bottoms of the compartments. The lubricating oils upon leaving the nozzles float upwardly through the water in the vertical oil passageways 10 and then horizontally through the passageways 11 and out through the outlet pipes 7. The steam and water passing through the equalizing passageways to the outlet pipes produce an ejector action in the passageways 11, picking up the lubricating oils and carrying the same through the outlet pipes.

35 60 From the above description, it will be readily seen that I have provided a single locomotive lubricator having separate lubricant compartments which are adapted to be operatively connected to different steam pressure cylinders.

What I claim as my invention is:

1. In a lubricator, the combination with the condensing chamber, of a plurality of lubricant compartments adapted to communicate therewith, separate filling openings for each compartment, lubricant outlet pipes adapted to communicate with said compartments, and steam equalizing passageways communicating with said outlet pipes. 70

75 2. In a lubricator, the combination with the condensing chamber, of a plurality of lubricant compartments therebelow and adapted to communicate with its lower end, separate filling openings for each compartment, a lubricant outlet pipe adapted to communicate with each of said lubricant compartments, and a steam equalizing passageway communicating with each of said lubricant outlet pipes. 80

85 3. In a lubricator, the combination with a condensing chamber, of a plurality of lubricant compartments below said condensing chamber and adapted to communicate with the lower end thereof, a single valve for controlling the communication between said compartments and condensing chamber, a lubricant outlet pipe at the upper end of each of said compartments and adapted to communicate therewith, and steam equalizing passageways leading from above said condensing chamber to said outlet pipes. 90

95 4. In a locomotive lubricator, the combination with the body having a condensing chamber in its upper portion, of a transverse wall in its lower portion forming a pair of lubricant compartments, separate filling openings for each compartment, passageways in said body for placing said condensing chamber in communication with each of said compartments, a single valve controlling the condensate flowing to both of said compartments through said passageways, lubricant outlet pipes, vertical lubricant passageways in said body adapted to communicate with said outlet pipes and each of said compartments, and steam equalizing passageways communicating with said lubricant outlet pipes. 100

105 5. A lubricator comprising a pair of lubricant compartments adapted to hold different grades of lubricant, independent filler plugs for each chamber, a common condensing chamber, passageways leading from said condensing chamber to each compartment, means for regulating the condensate delivered to each compartment, lubricant outlet pipes leading from each compartment, steam equalizing passages connected with each outlet pipe and separate regulating means for each outlet pipe for respectively controlling the amount of lubricant delivered from each compartment. 110

115 6. A lubricator comprising a casing having a pair of separate lubricant compartments. 120

ments therein, separate inlet means for each compartment permitting independent filling of the respective compartments with different grades of lubricant, a common condensing chamber having a single condensate outlet, a single control valve in said condensate outlet, a pair of branch passageways leading from said single condensate outlet to the

respective compartments, lubricant outlet pipes leading from each compartment, ¹⁰ steam equalizing passages connected with each lubricant outlet pipe, and separate regulating means for each lubricant outlet pipe.

In testimony whereof I affix my signature.
FREDERICK C. BLANCHARD.
